A device for holding a pair of eye-glasses, comprising a pair of opposed rack like structures, or conformations, disposed lengthwise of the device, and adapted to receive and support the two lenses of a pair of spectacles, the upper ends of the rack like structures being connected to a horizontal top, or cross member, and the lower ends of the rack like structures being connected to a pair of opposed end members, the ends of the rack like structures being bent forwardly to terminate in downwardly curved members, and the ends of the opposed end members being bent forwardly to terminate in downwardly curved members, and the ends of the rack like structures being bent rearwardly to terminate in downwardly curved members, and the ends of the opposed end members being bent upwardly to terminate in upwardly projecting back or rear brace members, the ends of the rack like structures being spaced apart from each other to provide a gap for the nose piece of the spectacles, and the ends of the opposed end members being spaced apart from each other to provide a gap for the nose piece of the spectacles.

UNITED STATES PATENT OFFICE

2,226,684

SPECTACLE HOLDER

William Enders Wortham, Franklin, Ky.

Application January 9, 1939, Serial No. 249,857

3 Claims. (Cl. 248—302)

This invention relates to a spectacle holder.

An object of the invention is to provide a device of the character described specially designed for the purpose of holding a pair of eye-glasses, when not in use, and for use in automobiles, trains, home, office, workshop and similar places.

A further object of the invention is to provide a new and useful holder specially formed to receive and support the lenses of spectacles in individual rack like conformations, lengthwise of the holder, so spaced apart and connected as to provide a gap therebetween for accommodating the nose piece of the spectacles.

A further object of the invention is to provide the device with means for easily and readily attaching the same to and detaching it from a supporting object.

With the above and similar objects in view, the invention consists in the novel features of construction, arrangement and combination of parts, hereinafter more clearly described and finally pointed out in the claims hereto appended.

Referring to the accompanying drawing forming a part of this specification, wherein like characters of reference denote similar parts throughout the several views:

Fig. 1 is a front elevation of the invention.

Fig. 2 is a side elevation of the invention.

Fig. 3 is a top plan view of the invention.

Fig. 4 is a detail of the mid-portion of the invention in rear elevation.

Fig. 5 is a modified form of the mid-portion of the invention in rear elevation.

Fig. 6 is a further modified form of the mid-portion of the invention in rear elevation.

Fig. 7 is a side elevation of the invention including the modification shown in Fig. 6.

Fig. 8 is a still further modification of the mid-portion of the invention in rear elevation.

In the embodiment of my invention, as shown in the drawing, the holder is made of suitable wire which is bent to provide a back section and includes a horizontal top, or cross member 1, and deformed upwardly midway its ends to form an inverted U-shaped socket member 2, and the ends of the wire are bent to terminate in downwardly and outwardly inclined end members 3.

The lower ends of the end members 3 are bent forwardly to terminate in downwardly curved spectacle lens supporting members 4.

The forward ends of the lens supporting members 4 are bent to terminate in upwardly curved front spectacle lens guard members 5.

The inner ends of the lens guard members 5

are bent rearwardly to terminate in downwardly curved members 6, which members 6 are disposed at a slightly higher elevation than the downwardly curved spectacle lens supporting members 4, and, the members 6 are suitably spaced apart from each other to provide a spectacle nose gap 7 midway the ends of the holder.

The rear ends of the downwardly curved members 6 are bent upwardly to terminate in upwardly projecting back or rear brace members 10 8, which are also spaced apart from each other and are suitably secured at their upper ends to the top cross member, as at 9.

The upper ends of the brace members 8 after they have been suitably secured to the top back 15 member 1, can be extended to terminate in downwardly projecting pin like members 10 having the pointed lower ends 11 for attaching the holder to supporting object which will permit penetration of the pins 10 thereinto. 20

The members 1, 3, 4, 5, 6 and 8 are so formed and arranged relative to each other as to form a pair of opposed rack like structures, or conformations disposed lengthwise of the holder and designated, generally, as A and B and adapted to 25 receive and support the two lenses designated 12 and 13 of a pair of spectacles, as clearly shown in Figs. 1 and 2 in dotted lines.

It will be apparent from Figs. 1 and 2 that lenses 12 and 13 are supported by the members 30 4 which connect the end members 3 at the back of the holder with the outer ends of the lens guard members 5, which members are spaced from the back of the holder, and, in side elevation, are inclined forwardly from the back of the 35 holder, as clearly shown in Fig. 2, so that the mouth at the upper ends of each rack like lens receiving and supporting structure A and B will be wider from front to back than the lens supporting members 4, and the members 6, from 40 front to back, thus permitting spectacles or eye-glasses to be supported in a forward leaning position, which makes it easy to remove the glasses from the rack like conformations A and B and to place spectacles or eye-glasses therein 45 from the top thereof.

It will be observed that the nose piece 14 of the spectacles spans the gap 7 and that the lenses 12 and 13 do not engage and are therefore not supported by the members 6 which connect the 50 inner ends of the lens guards 5 with the brace members 8.

In Figs. 1 and 2, a suitable rubber vacuum cup 15 is shown as carried by the inverted U-shaped loop 2 for attaching the holder to a vertical sup- 55

porting surface. The cup 15 is provided with a neck 16 receivable in the loop 2 from the lower open end thereof and the neck 16 is provided with a head 17 engaging the front face of the loop 2.

As shown in Figs. 2 and 4, the holder can be provided with a loop 2 for carrying a rubber vacuum cup 15 and fastening pins 10, so that the holder can be attached to a supporting object either by the vacuum cup, or the fastening pins.

As shown in Fig. 5, the holder is provided with only the loop 2 adapted to carry or support a vacuum cup and is minus the fastening pins 10.

As shown in Figs. 6 and 7, the holder is shown as provided with fastening pins 10 only, the loop 2 shown in Figs. 2 and 3 being omitted in the structure.

As shown in Fig. 8, the holder is provided with a modified form of loop designated 2' and designed to carry a screw or nail 18 for attaching the holder to a supporting object instead of with a vacuum cup 15 or supporting pins 10.

As shown in Figs. 1, 2 and 3, the curved lens guard members 5 are provided with a suitable rubber, or the like covering 19 to prevent the guard members 5 from scratching the lenses of eye-glasses carried by the racklike formations A and B of the holder. In Fig. 3 of the drawing, the rubber covering for the guard members 5 is shown as partly broken away from the inner ends thereof. It is to be understood that the protective covering on the guard members 5 can be omitted, if so desired.

The many advantages of the herein described invention will readily suggest themselves to those skilled in the art to which the invention appertains.

From the foregoing description, it is evident that a simple device for this purpose has been disclosed, but it is to be understood that I do not desire to restrict, or limit myself to the very details of the construction shown and described, which is merely illustrative, it being obvious that changes, not involving the exercise of invention, may be made without conflicting or departing from the spirit of the invention within the scope of the appended claims.

What I claim is:

1. A spectacle holder formed from a single piece of wire deformed midway its ends to provide an inverted U-shaped loop adapted to support a fastening device for attaching the holder to a

supporting object, the ends of the loop projecting horizontally therefrom in opposite directions to provide back sections, the outer ends of the back sections terminating in downwardly projecting sections disposed at obtuse angles to the back sections, the lower ends of the downwardly projecting sections terminating in forwardly projecting sections, said latter sections terminating in front upwardly curved forwardly inclined lens engaging sections terminating at their inner ends opposite each other with a gap therebetween, said front upwardly curved inclined sections terminating in rearwardly projecting sections spaced from each other, and said rearwardly projecting sections terminating in upwardly projecting sections secured at their ends to the back sections adjacent the base of the loop.

2. A spectacle holder comprising a wire bent to form a top cross wire deformed midway its ends and inclined downwardly at its ends, the lower terminals of the inclined ends of the back wire being bent forwardly a short distance to provide lens supports and then terminating in upwardly curved forwardly inclined lens guard wires having their inner ends spaced apart and bent rearwardly to provide lens supports which terminate in vertical back wire portions spaced from each other and secured at their upper ends to the top cross wire, and a covering for the upwardly curved forwardly inclined lens guard wires.

3. A spectacle holder having, in combination, a single length of wire fashioned to provide a top back cross member upwardly deformed midway its ends to provide a loop, the ends of said member terminating in downwardly projecting end members, the lower ends of the end members terminating in forwardly projecting lens supports, said lens supports terminating in front upwardly curved forwardly inclined lens guards terminating at their inner ends in spaced relation to each other, the inner ends of said lens guards terminating in rearwardly projecting members which in turn terminate in upwardly projecting back members secured at their upper ends to said top back cross member on opposite sides of the deformed mid-portion thereof, and the upper ends of said upwardly projecting back members terminating in rearwardly and downwardly projecting members having their free ends pointed.

WILLIAM ENDERS WORTHAM.
